UNITED STATES PATENT OFFICE.

ARTHUR T. O'DEA, OF PITTSBURGH, PENNSYLVANIA.

METAL CRATE.

1,408,392.

Specification of Letters Patent. Patented Feb. 28, 1922.

Application filed October 23, 1920. Serial No. 418,959.

To all whom it may concern:

Be it known that I, ARTHUR T. O'DEA, a citizen of the United States, and a resident of Pittsburgh, in the county of Allegheny and State of Pennsylvania, have made a new and useful Invention in Metal Crates, of which the following is a specification.

My invention relates to shipping containers and consists in a metallic crate 10 adapted for flat, flexible merchandise.

My crate has been designed especially for use in shipping paper and one of the objects of my invention is to present flat surfaces next to the paper. Other objects are 15 to secure an adjustable, light, compact, strong and economical crate.

These objects are obtained by the use of the metal fabricating element illustrated in the accompanying drawings in which 20 Figure 1 is a top view of my improved crate; Figure 2 is a side view of the same; Fig. 3 is a horizontal section through one corner taken on line 3—3 of Fig. 2; Fig. 4 is an isometric view of two crate members 25 adapted to be assembled to form the joint indicated at A in Figure 1; Fig. 5 is a view of a staple used in uniting the upper and lower portions of the crate, and Figs. 6 and 30 7 show modified sections which may be substituted for my preferred fabricating element.

The crate is formed substantially of longitudinal lengths 1 and transverse lengths 2 and 3 of the fabricating element best shown 35 in Fig. 4. A few simple parts 4 and 5 are used to unite these lengths. The main fabricating element consists of a long, relatively narrow piece of sheet metal bent or drawn to form the hollow, T section illustrated. It is apparent that such a section 40 possesses a high degree of rigidity for its weight and will resist bending in any transverse direction.

This inherent rigidity is increased when 45 the lengths are combined as shown in my crate construction with the cross bar of one element 1 disposed vertically and the cross bar of another element 2 disposed horizontally. The hollow, T section is readily 50 adapted for assembly of the elements when so disposed as is illustrated in Figures 1 and 4. Here the leg of element 1 is slotted transversely at 6 and 7 at points adapted to receive the ends of the cross bar of element 55 2. The tongues 8 and 9 of element 1 will

be received in the hollow cross bar of element 2 and have a spring-like bearing therein.

The longitudinal elements 1 and transverse elements 3 are connected at the corners 60 of the frame by inserting both flanges of the leg of the one element between the corresponding flanges of the other element. In this assembling operation, a flat band 4, bent into a right angle, is inserted in the 65 hollow cross bar of each T element. After assembly, band 4 and elements 1 and 3 are further secured together by inserting a pin through both of them. In the crate shown, this pin forms the bent end 10 of a staple 70 5 which also unites the upper and lower members of the crate. It is an easy matter to vary the length of staple 5 to adapt it for different depths of crates.

As the sheet metal from which the T- 75 shaped elements are formed need not be very thick, it will be seen that the offset between two adjacent elements at their joint will be so slight as to afford no damage to material contained in the crate. 80

The method of assembling the upper and lower crate members facilitates the formation of different heights of crates for different quantities and thicknesses of sheets contained therein. 85

The modified sections shown in figures 6 and 7 illustrate other forms of the hollow, T section which may be found advantageous. I believe the hollow, T-shaped fabricating element to be a novel section 90 and adapted for other uses than in shipping crates.

While I have referred to my crate as being especially adapted for shipping paper, it may be well used, in its present or a 95 modified form, for tin plate, steel or other metal sheets, wall board, veneer, etc. and in any of these uses, its rigidity, economy and adaptability shows a material advantage over other crates now in use. 100

I claim:—

1. A crate frame including longitudinal members comprising hollow angular members formed of sheet metal and having the edges of the sheet metal spaced apart to form 105 a projecting flange and notched at intervals to form a double tongue, and hollow angular transverse members extending at right angles to said longitudinal members and having their ends engaged by said tongues 110

whereby each double tongue projects into the hollow interior of the member and extends longitudinally thereof.

2. A crate frame including interlocking longitudinal and transverse members, each member comprising a hollow angular member formed of sheet metal with the portions of the sheet forming the opposite sides of each flange portion spaced apart, and tongues formed on some of said members by cutting parallel slots therein at right angles to the axis thereof said tongues projecting longitudinally into the end of an interlocked member.
3. In a crate, parallel, hollow, T shaped elements, parallel, hollow, T shaped elements arranged transversely thereto the cross bar of one of said elements terminating near the cross bar of an adjacent element an L shaped corner band inserted in the adjacent cross bars, and band and element retaining means.
4. A metal crate frame, including hollow T-shaped members formed of sheet metal and interlocked by means of tongues, formed on one member by having parallel slits cut into a flange portion thereof, and projecting into and extending longitudinally of the interior of the interlocked member.
5. In a crate composed substantially of long elements each having a hollow, T shaped section; a disposition of said elements so that the edge of the leg of one element is disposed towards the end of the cross bar of another element, said leg being slotted at intervals so as to provide a tongue portion adapted to enter said hollow cross bar.
6. A crate frame composed of hollow, T shaped elements, in which the legs of elements forming opposite sides of the frame are positioned horizontally and the cross bar of elements intermediate said sides are positioned horizontally, said legs being cut to form tongues adapted to enter the ends of said cross bars.
7. In a crate, parallel, angular elements, parallel, angular elements arranged transversely thereto, one of the flanges of each element consisting of a hollow portion and terminating near a hollow portion of a transverse element, an L shaped corner band in-

serted in the adjacent hollow portions, and band and element retaining means.

8. In a crate frame comprising hollow T-shaped members, an L-shaped corner band projecting into the hollow cross bar portions of adjacent members and hollow T-shaped members extending transversely of some of said first mentioned members and interlocked therewith by means of tongues formed thereon by slitting flanges thereof, each of said tongues projecting into the hollow cross bar portion of one of said transverse members and extending longitudinally thereof.

9. A fabricating element for crates formed of sheet metal overlapped upon itself to form a base portion and a projecting flange, and having assembling tongues formed thereon by having slits cut at intervals in the flange portion thereof.

10. A fabricating element of a metal crate T-shape in cross-section formed of sheet metal overlapped upon itself to form a base portion, and a flange extending longitudinally of the base and projecting at right angles thereto intermediate the lateral edges thereof, and a tongue formed thereon by slits cut into the edges of the sheet metal at an angle to the axis of the base portion.

11. A fabricating element of a metal frame having a T-shaped cross-section and consisting of a hollow base portion and a double flange projecting at right angles therefrom with each portion of the double flange integrally formed with the adjacent portion of the base, and assembling tongues formed on said element by parallel slits cut into the flange portion thereof.

12. A fabricating element of a metal frame comprising a hollow flanged member formed of sheet metal and having the edges of the sheet metal spaced apart to form a projecting flange and notched at intervals to form a double assembling tongue.

In testimony whereof, I have hereunto subscribed my name this 15th day of October, 1920.

ARTHUR T. O'DEA.
